ANTENNA SYSTEM

Hendrik C. A. van Duuren, Wassenaar,
NetherlandsApplication December 21, 1940, Serial No. 371,176
In the Netherlands December 21, 1939

17 Claims. (Cl. 250—33.55)

1

The present invention relates to a directional antenna system for wireless reception comprising a plurality of rhombic antennae of similar form and similarly arranged, such as in horizontal end-to-end array. These antennae have lead-in connection from corresponding angular points of each rhomb, each constituting a lead-in point for the rhomb, and each rhomb has maximum effectiveness of reception in a vertical plane which extends symmetrically through the rhomb from the lead-in end to the opposite or terminating end. In this end-to-end array, the maximum effectiveness of reception lies in a direction which is the same for all rhombs, this direction extending at an angle to the horizontal and being a function of the length of the wave received. A well known system of this general type is known as the MUSA system (abbreviated from Multiple Unit Steerable Antenna) which is described in the Bell System Technical Journal of 1937, pages 337 et seq. This MUSA system utilizes a number of rhombs arranged end-to-end in a row and connected to each other and to the receiver by the way of phase rotators or phase shifters which permit of the modification, within certain limits, of this angle of directivity in the vertical plane from which the combination of rhombs receives signals with maximum effectiveness for a given wave length.

It is a requirement of this MUSA system, as will hereinafter appear, that each successive phase shifter shall shift the received current through an angle which, with respect to that of the first phase shifter, is greater by a factor which is a whole number. This necessitates an expensive arrangement.

The directional characteristic of these multiple unit antennae systems having steerable directivity can be deduced or determined from one directional characteristic which depends only on the position of the individual antenna relatively to each other and to their interconnection (hereinafter referred to as the "group directional characteristic") and also from the directional characteristic of a single rhomb (hereinafter referred to as the "individual directional characteristic"). The relative transmitting or receiving intensity in a certain direction is proportional to the product of the intensities of the above two directional characteristics for the given direction.

For satisfactory reception from a given direction, the two directional characteristics for the direction concerned must have a sufficient intensity. The systems of the prior art have the operating disadvantage that, when the condition

stated above for reception from a given direction and at a given wave length is satisfied, the device cannot be used for a different wave length at a given adjustment of the phase shifters, because 5 the single rhomb directional characteristic and the group directional characteristic, which have now both been modified, have as a rule such a different orientation that from no direction is suitable reception possible. The single rhomb 10 directional characteristic cannot be modified by simple means.

The group directional characteristic, however, can be varied by the introduction of differences 15 in propagation time of which the values increase equally in the lead-in feeders of the individual rhombs, which variation may be attained by means of the phase shifters referred to above. These phase shifters in such prior art systems must be adjusted in a different way for each 20 wave length.

These prior art systems employing numerous phase shifters are rather expensive, and hence the problem arises of providing an antenna system which is suitable for the reception of different 25 wave lengths without phase shifters or with other means to be adjusted for each separate wave length.

In effecting the solution of that problem, it is 30 necessary that the group directional characteristic and the individual rhomb directional characteristic shall have for each different wave length substantially the same orientation relatively to each other, which orientation in itself 35 will depend, of course, on the wave length.

One of the features disclosed in the present invention is the provision of a system wherein two or more rhombic antennae are placed with their lead-in feeding points in such spaced relation, and are connected to the receiver by means 40 of transmission lines having such differences in propagation time, that the angle of maximum sensitivity or effectiveness for each frequency in the aforesaid vertical plane, within at least an octave of frequencies, is equal, or almost equal, for both the group directional characteristic and the individual rhomb directional characteristic.

With such a system, the directional properties or directional effect cannot be controlled in the way that is possible when phase shifters are utilized. However, this control of directional effect is possible when employing two or more of these systems with the systems interconnected over phase rotators or phase shifters. Compared 55 to the relatively small angle of directivity in

which reception is possible at a given wave length when using one such a system, a finer selection is possible in the arrangement of the present invention. In this way, the same directional definiteness can be attained that is possible in a system comprising the same total number of rhombic antennae as in the present invention, but each separately connected over a phase rotator.

At each wave length, however, the limits of the angular span of steerable directivity in which transmitting or receiving intensity is of satisfactory strength (in which satisfactory strength may be defined, for example, as 50% of the maximum receiving power) are closer than with a device in which all rhombs are coupled over phase rotators.

If it should be necessary to have available a wider span or interval of steerable directivity, another series of rhombs differently dimensioned can be utilized for the next interval, and so on.

As these series can be arranged in superposed relation over the same space of ground, no further space is required to this end.

In one preferred embodiment of the invention, two series of rhombs are used, each series consisting of two groups of rhombs, there being a phase shifter between the two groups of each series. The groups of the first series each have two rhombs, and the groups of the second series each have four rhombs. Such a combination permits of directive control between two angles, the sines of which are 1:2.8. This is amply sufficient, since a rhombic array according to the MUSA system is variable between two angles, the sines of which are related as 1:2.45 with the above power condition or requirement.

In this preferred embodiment of the present invention, four feeders arrive at the receiver, one from each group of rhombs. These feeders are terminated at the receiver and are connected to the input of a high frequency amplifier. The outputs of two of these high frequency amplifiers, one associated with one series of rhombs and the other associated with the other series of rhombs, are connected to phase shifters, which may again be followed by high frequency amplifiers. The outputs of these devices are, insofar as they are associated with groups of rhombs of the same series, paralleled on the input of a receiver arranged to rectify the signal. The receiver outputs, which correspond in number to the number of series of rhombs, are paralleled on the low frequency output by way of networks for correcting differences in propagation time. Since the various series of rhombs are adjusted to different angles, they receive rays which, having been emitted simultaneously, arrive with different retardations. It may be pointed out here that the wide band characteristic mentioned at the end of the above-mentioned article of the Bell System Technical Journal on the MUSA system therein described relates exclusively to very narrow bands, as compared with an octave.

The invention will be exemplified below with reference to the accompanying drawing illustrating one preferred embodiment of the invention. In this drawing:

Figure 1 is a diagram representing the received voltage as a function of the angle of wave arrival for one rhomb and for combinations of rhombs; and

Figure 2 is a diagram schematically illustrating the antenna system, together with the connections with the receivers, etc.

Referring first to Figure 2, this figure illus-

trates two separate series of rhombic antennae, one series being indicated by the rhombs designated 1 to 4 inclusive, and the other series being indicated by the rhombs designated 9 to 16 inclusive. In the first series, 1-4, the two rhombic antennae 1 and 2 constitute one group, and the other rhombic antennae 3 and 4 constitute a separate group. These two groups are connected in group arrangement by fixed feeders 5 and 6 for the first group, and by fixed feeders 7 and 8 for the second group, the points of juncture of the respective pairs of feeders being indicated at 50 and 51. Each pair of feeders is connected to the left hand extremity of its respective rhomb. The right hand extremity of each rhomb is shown as being terminated by a terminating resistance 55 which equals the characteristic antenna resistance.

The other series of eight rhombic antennae 9-16 is likewise divided into two groups, one group consisting of the rhombs, 9, 10, 11 and 12, and the other group consisting of the rhombs 13, 14, 15 and 16. The first group of rhombs 9-12 in this second series is provided with pairs of feeders 17, 18, 19 and 20, respectively, which have a point of juncture indicated at 25. The second group of rhombs 13-16 in this second series also has pairs of feeders 21, 22, 23 and 24 which have a point of juncture indicated at 26. The mutual or interspacing distances of the rhombs and the lengths of their connecting lines, both between the two groups of antennae and between the receivers and the junction points 51 and 26, must satisfy certain requirements in order that the combinations of rhombs shall have the same directional characteristic as a single rhomb with regard to dependence of the angle for maximum effectiveness of reception on a given frequency or wave length. In this regard, the difference of the distances from juncture point 51 and its companion juncture point 26 to the receiver, as compared to the distances from juncture point 50 and its companion juncture point 25 to the receiver, should be taken into account, and not these distances themselves. An effort has been made to indicate this in the drawing by inclined lines. The above dependence of the angle on frequency is of such nature that, for a given antenna construction, at a certain wave length λ_0 , a given angle of arrival Δ_0 will result in maximum effectiveness of reception. The relation between wave length λ and the angle Δ for which the reception remains a maximum, may be stated for small angles to be approximately:

$$\sin \Delta = \sqrt{\frac{(2\lambda - 1)}{\lambda_0}} \times \sin^2 \pi_0$$

This formula is also valid for a series of rhombs if the distance of two of these is given by

$$\frac{1}{2} \frac{\lambda_0}{\sin^2 \Delta_0 \cos \Delta_0}$$

and if the length of their connecting line equals—

$$\frac{1}{2} \frac{\lambda_0}{\sin^2 \Delta_0} + \frac{\lambda_0}{2}$$

with the further condition the connecting line between each pair of adjacent rhombs is crossed, being moreover satisfied. The distances, i. e. the lengths according to the above formulae may also be several times larger; if this is an even number of times, the crossings of the connecting line leads should be omitted.

The series of large rhombs 1, 2, 3 and 4 is built in accordance with the above description and equations. Similarly, the lengths of the feeders 5 and 6 with their connection at junction point 50, and also the lengths of the feeders 7 and 8 with their connection at junction point 51, are proportioned or chosen in accordance with the above conditions. The difference in length of the lines from point 50 to the receiver in comparison with the length of the lines from point 51 to the receiver is of such value that, according to the above formula, the immediate paralleling of the lines from points 50 and 51 to the receiver will establish for the series of rhombs 1, 2, 3 and 4 a dependence in the above sense which is equal to that of a single rhomb.

The foregoing also applies to the series of eight rhombs 9-16, inclusive, making up the two groups of rhombs 9-12 and 13-16, respectively.

The lines coming from the points 50, 51, 25 and 26 are led to the receivers through tubes 27, 28, 29 and 30 and arrive at input transformers 35, 36, 37 and 38.

The rhomb dimensions may be calculated according to the methods given in the article by Bruce appearing in Proceedings of the Institute of Radio Engineers of January 1935, starting on page 24, and more particularly according to the Alignment Design Method appearing on page 30.

Referring to the values ψ and l appearing at rhomb 1 in Figure 2, we have, according to the above method:

$$\psi = \Delta_0 \text{ and } l = \frac{0.371 \lambda_0}{\sin^2 \Delta_0}$$

It has been found that the sides of the rhombs 1 may also be made smaller. For $\alpha > 1$ e. g. the angle ψ and the side l may be chosen in accordance with the formulae

$$\sin \psi = \alpha \text{ and } l = \frac{0.371 2\lambda_0}{(1 - \alpha^2) \sin^2 \Delta_0}$$

If α is chosen smaller than 2, the maximum will, in comparison to Bruce's method, remain in this "Reduced" project, practically in the same place. If $\alpha = \sqrt{2}$, the rhombs will become so much smaller that the adjacent angular points of subsequent rhombs of each series may be suspended on the same mast. Of course, the length may also be calculated according to Bruce, and the system will then consist of rhombs in which every succeeding rhomb somewhat overlaps the previous one. From the point of view of operation there is no objection to this, but more poles will be required.

At the receiver shown at the left hand side of Figure 2, the transformers 35, 36, 37 and 38 lead to the high frequency amplifiers 31, 32, 33 and 34. It will be noted that the amplifiers 31 and 33 have phase rotators 39 and 40 interposed in their outputs. Beyond these phase rotators, the outputs of the two amplifiers of each series are connected together in parallel relation, as indicated at 41 and 42, respectively. Interposed in these parallel connections 41 and 42 are receivers 43 and 44 which rectify the signals. In the output circuit of one of these receivers is connected a retardation or delaying network 45 for correcting differences in propagation time. Beyond this retardation network 45, the outputs of the two receivers are paralleled to the common output 46 leading to a conventional translation device.

The two series of rhombic antennae 1-4 and 9-16, respectively, may be continuously in simultaneous operation.

It has been found possible with the system described to control angles of arrival in a sector between 8° and 20° from the horizontal.

The choice of a definite angle within this sector is effected by means of the phase rotators 39 and 40, the action of which will be explained in connection with Figure 1.

This Figure 1 shows some characteristics of rhombic antennae and combinations of rhombs. On the horizontal axis, the proportion of $\sin \Delta : \sin \Delta_m$ has been set out, the value of Δ_m giving the angle for which the rhomb or combination of rhombs supplies maximum current to the receiver. The ordinates in this Figure 1 are currents. It should be observed that actually the diagram should be constructed as a function of the angle. However, it has been found that the plotting of the characteristics as a function of the independent variable chosen gives a curve which, with a considerable degree of exactness, is valid for any value of Δ_m when this value is less than approximately 30° , as will be the case in practical operation. The maxima of the different curves have been taken as equal. Curve *a* is for a single rhomb, *b* for two rhombs, *c* for four rhombs and *d* for eight rhombs. If the rhombs are all of equal size, the maximum of curve *d* would be eight times as high as that of curve *a*; the scale is thus eight times as small for curve *d*.

The curves given are valid for an adjustment of the phase rotators in which the latter do not bring about a phase rotation. Let us now see how the curve of the 8-fold series varies with displacement of the phase rotator 40. From such description, the action of the other phase rotator 39 will then be easily understood.

The 8-fold series consists of two groups of four rhombs, according to which characteristic *c* should be used. If phase rotator 40 is varied, the currents of the two curves *c* will no longer be in phase in the maximum, but the currents of both groups are mutually in phase for an angle, which is different from that of the original maximum, it will be clear that the point of maximum reception for the series of 8 rhombs will be displaced. It has been found that this displacement may be continued until the current value has been reduced to about $\frac{1}{2}\sqrt{2}$, without undue increase of the secondary maxima or side loops, which are not shown in the figure.

In operation, the maximum of each series of rhombs will be so adjusted that it yields maximum reception, in connection with the direction from which the rays arrive. Therefore, the receiving station should preferably be provided with apparatus permitting of the measurement of the signal strength behind each series of rhombs separately.

If receiving conditions are particularly unfavorable, the combination of receptions of the two series of rhombs on the output 46 may be dispensed with, i. e., one of the series of rhombs may remain entirely unused. Transformers 35 and 37 and the associated transformers 36 and 38 may also be paralleled when one of the series of rhombs is put out of action, because no strong dependable signals may be received thereon. It may be that when using such a circuit connection the introduction of intermediate amplification becomes desirable. With such circuit, the two phase rotators 39 and 40 will be in connection with a single series, and consequently two rays or waves from the reception range of that series are susceptible of isolation and of being fed to the receivers 43 and 44.

I claim:

1. A directional antenna system for a wireless receiver comprising a group of rhombic antennae in end-to-end array, each of the rhombs of said group having maximum effectiveness of reception in its vertical plane from a direction which is the same for all rhombs and the angle of which is displaced from the horizontal and is a function of the length of the wave received, two or more of said rhombs being located with their feeding points at spacing distances substantially represented by

$$\frac{1}{2} \frac{\lambda_0}{\sin^2 \Delta_0 \cos \Delta_0}$$

and leads connecting said spaced rhombs with the receiver having lengths substantially represented by

$$\frac{1}{2} \frac{\lambda_0}{\sin^2 \Delta_0} + \frac{\lambda_0}{2}$$

in which λ_0 = wave length and Δ_0 = angle of arrival above a horizontal plane for which maximum reception is obtained with the given wave length and antenna construction, whereby with a given frequency change in a given range of frequencies the directional characteristic for the group of rhombs is oriented to a new angle of maximum effectiveness which is substantially equal to the angle of maximum effectiveness established for a single rhomb with the same frequency change.

2. A directional antenna system as claimed in claim 1 characterized by the fact that there is a plurality of groups of rhombic antennae in end-to-end array, said groups being arranged in series relation and each group having the interconnections therebetween as set forth in claim 1, each two groups of said series having an individual phase rotator for interconnecting the output paths of the antennae of its associated two groups.

3. In a directional antenna system, the combination of a series of relatively large rhombic antennae in end-to-end array, a series of relatively smaller rhombic antennae in end-to-end array, one of said series being in superposed relation to the other, and translating means having common connection with both series of antennae.

4. In a directional antenna system the combination of a series of relatively large rhombic antennae in end-to-end array, a series of relatively smaller rhombic antennae in end-to-end array, each series comprising a plurality of groups of antennae, one of said series being in superposed relation to the other, phase shifting means connected between groups in one of said series, and translating means having common connection with both series of antennae.

5. In a directional antenna system the combination of a series of relatively large rhombic antennae in end-to-end array, a series of relatively smaller rhombic antennae in end-to-end array, each series comprising a plurality of groups, each group comprising at least two rhombic antennae, one of said series being in superposed relation to the other so that both series of relatively large antennae and relatively smaller antennae can be carried by the same supporting poles, independently operable phase shifters connected between groups in said two series, and translating means jointly controlling or controlled by both series of antennae.

6. In a multiple unit steerable antenna system,

7 the combination of a first series of rhombic antennae of relatively large size, a second series of rhombic antennae of relatively smaller size, each of said series comprising at least two groups, a phase rotator between the groups of said first series, a phase rotator between the groups of said second series, and translation means connected to both series of antennae.

8. In a multiple unit steerable antenna system, the combination of a first series of rhombic antennae of relatively large size, a second series of rhombic antennae of relatively smaller size, each of said series comprising at least two groups, a phase rotator between the groups of said first series, a phase rotator between the groups of said second series, one of said series being in superposed relation to the other, and a common output circuit connected to both series of antennae.

9. In a multiple unit steerable antenna of the 20 class described, the combination of a first series of rhombic antennae each of relatively large size, a second series of rhombic antennae each of relatively small size, each of said series comprising a plurality of groups, each group comprising at 25 least two antennae, there being at least twice as many antennae in each group of said second series as there are in each group of said first series, amplifiers for each of said groups, phase rotators connected only between groups in each 30 series, and a translation device connected in joint control relation with both series of antennae.

10. In a multiple unit steerable antenna of the 35 class described, the combination of a first series of rhombic antennae each of relatively large size, a second series of rhombic antennae each of relatively small size, each of said series comprising a plurality of groups, each group comprising at 40 least two antennae, there being at least twice as many antennae in each group of said second series as there are in each group of said first series, high frequency amplifiers for each of said groups, phase rotators connected only between groups in each series, said phase rotators being 45 mutually independent, receivers for each of said series, one of said series of rhombic antennae being in predetermined physical relationship to the other series of rhombic antennae, and a common output circuit jointly connected with both 50 series of antennae.

11. In a multiple unit steerable antenna of the 55 class described, the combination of a first series of rhombic antennae each of relatively large size, a second series of rhombic antennae each of relatively small size, each of said series comprising a plurality of groups, each group comprising at 60 least two antennae, there being at least twice as many antennae in each group of said second series as there are in each group of said first series, one of said series being in superposed 65 relation to the other, high frequency amplifiers for each of said groups, phase rotators connected only between groups in each series, said phase rotators being mutually independent, receivers for each of said series, a retardation network in the output of one of said receivers for correcting differences in propagation time, and a common output circuit on which the outputs from said receivers are paralleled.

12. In a multiple unit steerable antenna of the 70 class described, the combination of a first series of rhombic antennae each of relatively large size, a second series of rhombic antennae each of relatively small size, each of said series comprising a plurality of groups, each group comprising at

least two antennae, there being at least twice as many antennae in each group of said second series as they are in each group of said first series, amplifiers for each of said groups, phase rotators connected only between groups in each series, said phase rotators being mutually independent, receivers for each of said series for rectifying the signals, and a common output circuit on which the signals from said receivers are paralleled.

12. In a multiple unit steerable antenna of the class described, the combination of a first series of rhombic antennae each of relatively large size, a second series of rhombic antennae each of relatively small size, each of said series comprising a plurality of groups, each group comprising at least two antennae, there being at least twice as many antennae in each group of said second series as there are in each group of said first series, amplifiers for each of said groups, phase rotators connected between groups in each series, receivers for each of said series for rectifying the signals, a retardation network in the output of one of said receivers for correcting differences in propagation time, and a common output circuit on which the signals from said receivers are paralleled.

13. In a multiple unit steerable antennae system, the combination of a series of individual rhombic antennae units arranged in end on array, said series comprising a plurality of groups, each group comprising two or more of said individual rhombic units, and connecting leads extending from the feeding points of said rhombic units for connection with translation apparatus, the distances between feeding points of the units being substantially equal to:

$$\frac{1}{2} \frac{\lambda_0}{\sin^2 \Delta_0 \cos \Delta_0}$$

and the lengths of said connecting leads being substantially equal to:

$$\frac{1}{2} \frac{\lambda_0}{\sin^2 \Delta_0} + \frac{\lambda_0}{2}$$

(in which λ_0 =wavelength and Δ_0 =angle of wave arrival above a horizontal plane for which maximum reception is obtained with the given wave length and antenna construction.)

14. In a multiple unit steerable antenna of the class described, the combination of a series of individual rhombic antennae arranged in end-to-end array and each having a terminating resistance at one end of each rhomb and a pair of connecting leads extending from the other end, said series comprising at least two groups, each group comprising at least two individual antennae, a separate amplifier for each group connected jointly with the connecting leads from the two or more antennae of that group, the spacing distances between connecting lead ends of the two or more antennae in each group being substantially equal to

$$\frac{1}{2} \frac{\lambda_0}{\sin^2 \Delta_0 \cos \Delta_0}$$

and the lengths of the connecting leads extending therefrom, being substantially equal to

$$\frac{1}{2} \frac{\lambda_0}{\sin^2 \Delta_0} + \frac{\lambda_0}{2}$$

in which λ_0 =wavelength, and Δ_0 =angle of wave arrival above a horizontal plane for which maximum reception is obtained with the given wave length, thereby in addition to attaining a sharper directional characteristic than is achievable with

a single rhomb, the directional characteristic for the group of rhombs is oriented with a given frequency change to a new angle of maximum effectiveness which is equal to the angle of maximum effectiveness established for a single rhomb with said given frequency change, detector means receiving the output of said amplifiers, phase shifting means operatively interposed between one of said amplifiers and said detector means, and an output circuit leading from said detector means.

15. In a multiple unit steerable antenna of the class described, the combination of a series of individual rhombic antennae arranged in end-to-end array and each having a pair of connecting leads extending from one end, said series comprising at least two groups, each group comprising at least two individual antennae, a separate amplifier for each group connected jointly with the connecting leads from the two or more antennae of that group, the spacing distances between corresponding points of the two or more antennae in each group being substantially equal to

$$\frac{1}{2} \frac{\lambda_0}{\sin^2 \Delta_0 \cos \Delta_0}$$

and the lengths of the connecting leads extending from said latter antennae, being substantially equal to

$$\frac{1}{2} \frac{\lambda_0}{\sin^2 \Delta_0} + \frac{\lambda_0}{2}$$

in which λ_0 =wave length, and Δ_0 =the angle of wave arrival above a horizontal plane, for which maximum reception is obtained with the given wave length, whereby a sharper directional characteristic is attained and the angle of maximum effectiveness in the vertical plane, for a substantial range of frequencies is substantially the same for said group of antennae as for the individual antenna, output means receiving the output from said amplifiers, and phase shifting means interposed between one of said amplifiers and said output means.

16. In an antenna system of the class described, the combination of a first series of relatively large rhombic antennae arranged in an end on array, a second series of relatively smaller rhombic antennae in an end on array, the difference in size being operative to provide a wider range of wave lengths over which said system is adjustably responsive each of said series comprising a plurality of groups to provide a sharper directional characteristic, each of said groups comprising at least two individual antennae, there being a larger number of individual antennae in each group of said second series than there are in each group of said first series, leads extending from each individual antenna, and translation means having common connection with both said first and said second series of antennae through said leads, said antennae being arranged in a predetermined relative spaced relation and said leads being constructed of different lengths and arranged to effect with said predetermined antenna spacing, an angle of maximum effectiveness in the vertical plane for each frequency, which over a substantial range of frequencies is substantially the same for the group in each series as for the individual rhomb in that series.

17. In an antenna system of the class described, the combination of a first series of relatively large rhombic antennae arranged in an

end on array, a second series of relatively smaller rhombic antennae in an end on array, each of said series comprising a plurality of groups, each of said groups comprising at least two individual antennae, there being a larger number of individual antennae in each group of said second series than there are in each group of said first series, a first receiver for said first series, a phase shifter interposed between one of the groups of said first series and said first receiver, 10 a second receiver for said second series, a phase shifter interposed between one of the groups of said second series and said second receiver, a common output circuit for receiving the output from both of said receivers, and a retardation 15 network interposed between one of said receivers and said common output circuit.
